KNITTING MACHINE

Paul W. Bristow, Laconia, N. H., assignor to Scott & Williams, Incorporated, Laconia, N. H., a corporation of Massachusetts

Application December 30, 1948, Serial No. 68,114

24 Claims. (Cl. 66—135)

This invention relates to knitting methods and machines and has particular reference to circular knitting on machines of the superposed cylinder type involving provision for the making of wrap patterns.

One of the objects of the present invention is to provide improved wrapping methods and devices whereby elaborate patterning may be accomplished in particular involving the production of the so-called color-in-color work. In accordance with the invention pairs of wrap yarn carriers are associated with each other for the production of multiple color designs with provision for mutual control of the wrap yarn carriers by each other resulting in simplicity of operation.

A further object of the invention relates to the provision of improved selective devices particularly for the control of needles. In accordance with this aspect of the invention provision is made for the selection of different patterns to be followed in different portions of a stocking. The improved pattern selecting devices make possible, furthermore, a considerable extension of the pattern selections which may be effected by means of trick wheels of limited circumferential extent. In brief, this is accomplished by arranging on a single trick wheel a plurality of independent patterns which may be selectively chosen or caused to operate in sequence.

A further object of the invention relates to the provision of a safety mechanism to disconnect a press-off draw-thread mechanism when making plain fabric to avoid complete press-offs.

Still another object of the invention is to provide an improved slider controlled stop motion which will effect stoppage of the machine in the event that needle controlling sliders accidentally assume improper positions.

These and other objects of the invention particularly relating to details of construction and operation will become apparent from the following description read in conjunction with the accompanying drawings in which:

Figure 1 is a vertical axial section through the needle cylinders and the associated wrap yarn presenting mechanism of a knitting machine embodying the principles of the invention;

Figure 2 is a vertical sectional view constituting a continuation of the upper end of Figure 1;

Figure 3 is a fragmentary plan view showing in particular the mounting arrangement for various cams acting upon wrap yarn carriers;

Figure 4 is a vertical axial section illustrating in particular the arrangement of certain cams acting upon wrap yarn carriers and the construction of a wrap horn and adjacent parts;

Figure 5 is a fragmentary plan view partly in section showing in particular cams for controlling outward movements of wrap yarn carriers and the controls for these cams;

Figure 6 is an elevation looking in the direction of the arrow marked 6 in Figure 5;

Figure 7 is a developed inside elevation of various cams illustrated in Figure 5;

Figure 8 is a plan view showing in particular pattern control means for the selection of needles;

Figure 9 is an elevation partly in section, the elevation viewing the mechanism of Figure 8 in the direction indicated by the arrow marked 9 therein;

Figure 10 is an elevation partly in section showing certain elements of Figure 8 viewed in the direction of the arrow marked 10 in Figure 8;

2

Figure 11 is an elevation partly in section showing certain elements of Figure 8 as viewed in the direction of the arrow 11 therein;

Figure 12 is an elevation showing certain parts of Figure 8 as viewed in the direction of the arrow 12 therein;

Figure 13 is a horizontal section showing in particular certain safety interlocking devices designed to prevent press-off when making plain socks without transfer of needles to the upper cylinder;

Figure 14 is an elevation of the mechanism illustrated in Figure 13;

Figure 15 is an elevation illustrating certain devices for effecting interruption of wrapping;

Figure 16 is an elevation of the same looking at the right-hand side of Figure 15;

Figure 17 is a plan view of the mechanism illustrated in Figures 15 and 16;

Figure 18 is a plan view showing various devices in the machine particularly the mounting of wrapping abutments, an arrangement for needle levelling and a slider controlled stop motion;

Figure 19 is an elevation showing details of the mechanism of Figure 18;

Figure 20 is an elevation showing in particular a counterbalance arrangement for the wrapping assembly;

Figure 21 is a fragmentary elevation illustrating in particular the lower ends of a pair of wrap yarn carriers and means for maintaining them in their normal rest position;

Figures 22 and 23 are elevations illustrating in particular the interrelationships of a pair of wrap yarn carriers, certain cams for operating these carriers, being illustrated in section;

Figure 24 is a diagram showing a typical arrangement of butts for the control of wrap yarn carriers;

Figure 25 is a plan view showing the assembly of various cams for controlling the movements of wrap yarn carriers;

Figures 26, 27 and 28 are plan views showing the same cams as are illustrated in Figure 25 but in particular, illustrating these at different levels and showing in diagram, the paths of butts acted upon by the cams; and

Figure 29 is an inside development of various cams for control of rotating parts of the machine, certain of these parts being indicated in construction lines.

45 The knitting machine embodying the inventions indicated above is of the superposed cylinder type comprising a lower cylinder 2 and an upper cylinder 3. Arranged to slide in slots in the lower cylinder are sliders 4 adapted to engage the lower hooks of double hook latch needles 6, the upper hooks of which are engageable by sliders 8 in the upper cylinder.

The lower sliders 4 are provided with butts at two levels 10 and 12 as hereafter more fully described. The upper sliders 8 are provided with butts at two levels 16 and 18.

55 The cylinders are preferably provided with inserted fixed walls to define the slots for reception of the sliders and these walls 20 in the case of the upper cylinder terminate substantially above its lower end so that the lower portions of the slider slots are bounded not by stationary walls but

60 by movable walls of two alternative forms arranged to slide in the wall slots in the upper cylinder. One set of these indicated at 22 carry butts 26 and are provided with outwardly and downwardly sloping lower ends as indicated most clearly at 30 in Figures 23 and 29. The other slide-

65 able walls indicated at 24 are provided with butts 28 and have verge bit extensions such as indicated at 32 in Figure 29. The arrangement and functions of these lower ends 30 and the verge bits 32 will be hereafter described. The verge bits are located between the positions of needles 34 which, in the formation of broad ribs, are carried by sliders in the upper cylinder.

The cylinders are rotated and reciprocated in unison through the medium of a vertical shaft 34 which, through conventional gearing is driven by the lower cylinder and 75 which, through gearing indicated at 40 and 42, drives the upper cylinder. The present machine additionally involves the driving of a wrapping assembly which action is effected through gears 44 and 46, the former being carried by the shaft 34.

Arranged to cooperate with the needles are arcuate sinkers 48 which are provided with butts 50 arranged to

be acted upon by stationary cams 52 (see Figure 1) supported by a stationary cylinder 54 inside the lower rotating cylinder. This stationary cylinder 54 also supports the fabric guiding tube 56 provided with an extension 57.

The rotary support for the wrap yarn carrying means is indicated generally at 58 (Figure 1). It is secured to the gear 46 and includes a member provided with an annular groove 60, in which groove are received the rounded pivot-forming projections 62 of wrap yarn carriers 64 surrounded by spring bands 66 and 82. Dummy spacers 65 are provided in locations where wrap fingers are entirely missing so as to maintain proper tension conditions of the spring bands. As will appear hereafter, in some instances two wrap yarn carriers 64 and 64' are located side by side in a single slot; if only one carrier is desired in a slot, the position of the other may be filled by a dummy carrier which is similar to an active carrier except that it terminates short of a lower yarn-carrying end. It then may function to limit movements of the active carrier associated with it, in the fashion hereafter detailed. Each of the wrap yarn carriers 64 and 64' has an upper extension 68 received in a notch 70 in an individual jack 72. These jacks 72 are provided with ring slots arranged so that they may embrace an annular ring 74 carried by the support 58. In order to guide the jacks 72 for radial movement and to position them in fixed circumferential locations they are received in slots 76 in the support 58. Each of the jacks is provided with a plurality of butts 73. As will be evident hereafter, these butts may be selectively broken away so as to provide selection in the operation of the wrap yarn carriers.

Each of the wrap yarn carriers 64 and 64' is provided with a downward extension extending through the upper cylinder and guided at its upper end in a radial slot 80 in the support 58. The lower spring band 82 serves to urge the lower ends of the wrap yarn carriers inwardly. Butts 84 are provided on the wrap yarn carriers to provide for the positive inward movements of their lower ends and for the arrest of the outward movements of their lower ends.

At its lower end each wrap yarn carrier is provided with a radially directed extension 86 which has a downwardly extending branch 87 provided with the yarn guiding openings 88. The downwardly extending branches 87 are provided with smooth lower inner edge portions arranged to cam the wrap yarn downwardly as the wrap yarn finger or carrier is withdrawn inwardly following a wrapping movement. Beyond these openings each carrier is provided with an abutment-engaging extension 90.

The wrap yarn carriers 64 and 64' differ from each other only in the fact that the carriers 64 are provided with laterally extending ears 89 which, as is best indicated in Figure 21, cause the lower ends of two closely adjacent carriers 64 and 64' supported in the same slot 80 to remain spaced from each other so that the wrap yarns passing through the openings 88 are not subject to friction or snagging during the movements of the adjacent carriers relative to each other. The ears 89 are of such radial extent that during the limited relative radial movements of the adjacent wrap yarn carriers these ears are always in position to maintain the lower ends of the carriers circumferentially spaced from each other.

The wrap yarn carriers are prevented from having more than a limited radial relative movement by reason of their being provided with circular holes 91 in which, in the case of each pair of carriers, there is located a disc 93 which is of such smaller diameter than the holes 91 as will provide the desired limit of relative movement of the lower ends of the carriers, for example, in a typical case the movement is limited to about a half inch. As a result of this construction, if one of the carriers is moved outwardly the other will follow it with a definite radial lag of movement of its lower end. In similar fashion the outward movement of one carrier of a pair may be limited by interruption of the outward movement of the other. As will become evident hereafter this interrelationship imposed on the carriers is used in the control thereof. The thickness of each disc 93 is approximately double the thickness of the wrap yarn carriers and slightly less than the clearance provided by the slot 80 so that these discs float in the openings 91 and in the slots 80 without any possibility of being disengaged from either of the

5 pair of associated wrap yarn carriers. A similar disc arrangement is provided in the case of an active wrap yarn carrier associated with a dummy carrier, outward movements of the active carrier being restrained by the dummy carrier through their common disc 93 when outward movement of the dummy carrier is limited by a cam. The interdependence of the movable carriers will be clear from Figures 22 and 23 to which more detailed reference will be made hereafter.

4 A tube 92, the upper end of which is secured in the assembly 58, carries at its lower end a disc 94 which is provided with radial fins 96, the upper edges of which are turned, as indicated at 98, in a clockwise direction as viewed in plan (see Figure 21). These edges 98 provide rests for the purpose of definitely positioning the lower ends of the wrap yarn carriers which are flexed in a counterclockwise direction as viewed in plane in order to insure normal engagement with these edges. The disc 94 is notched as indicated at 95 in the sole section thereof between the fins 96 for the free passage of wrap yarns which extend in a stocking from a point of interrupted wrapping above the heel, past the heel and other regions where wrapping does not occur. The wrap yarns then lie sufficiently inwardly not to interfere with other operations.

Extending downwardly within the upper cylinder 3 is a stationary cylinder 100, this being interposed between the cylinder 3 and the wrap yarn carriers. The cylinder 100 is carried by a portion of the frame which supplies a lower bearing 101 for the rotating support 58. The specific mounting of this cylinder is later described.

An axially extending rod 102 is guided for lengthwise movement through the tube 92 and carries at its lower end a fabric take-up disc or pusher 104 provided with rounded fingers 106.

The rotating wrap yarn carrying assembly includes a disc 108 on which are supported the wrap yarn bobbins 110, of which there is one for each wrap yarn, only one of these being illustrated in the interest of clarity in Figure 1. The wrap yarns pass from these bobbins through the individual tension devices 111 and take-up sweeps 113 and thence downwardly through tubes 116 about the lower edge of the cylinder 100 (when the wrap yarn guides are outwardly projected) and through the eyes 88 in the individual wrap yarn carriers. The tension and take-up devices are of the type disclosed in the patent to Albert L. Oberholtzer, Number 2,506,968, dated May 9, 1950.

The wrap yarn supporting means is so arranged as to permit the entire wrap yarn assembly to be raised clear of the upper cylinder and swung to one side to permit threading or other manipulations of the wrap yarn carriers. The particular means for effecting this result will now be described.

5 A stationary tube 118 carried by the machine frame acts as a vertical guide for a tubular post 120 slidable and rotatable therein, which post is provided with a bracket 122 limiting its lowermost position by engagement with a bracket 128 carried by the upper end of the tube 118. The post 120 carries an arm 130 which is provided with an extension 132 carrying a conical member 134 arranged to be received in the upper end of a fixed tube 136. This arrangement provides a rigid mounting for an upper bearing 138 of the revolving wrap yarn carrying assembly and serves to align the assembly with the lower bearing 101 when the assembly is returned to an active position after being removed from this bearing. Within the bearing 138 is a running collar 140 to which is secured a tube 142 which extends downwardly and is secured at its lower end to the lower portion of the wrap yarn carrying assembly. Within the upper portion of the tube 142 is a cylindrical head 144 secured to the rod 102 previously mentioned. A pin 148 carried by the hub 149 of the disc 108 projects into a longitudinal slot 146 in the head 144 and so causes the head 144, the rod 102 and the take-up disc 104 to rotate with the wrap yarn assembly. When the rod 102 is in its uppermost position with respect to the assembly, with the disc 104 and the fingers 106 housed in the dished lower surface of the disc 94, a spring controlled latch 152 is so arranged that it can be entered into an annular slot 150 near the upper end of the head 144. (See Figures 8 and 9 of my Patent 2,555,870, dated June 5, 1951.) This latching of the rod 102 in its uppermost position is effected by hand operation when the wrap assembly is to be removed from the

upper cylinder; normally the rod 102 and the pusher are unlatched being automatically raised at the time of starting the broad rib in the leg and at the beginning of the ring toe, and being allowed to drop at the end of the heel and again at the end of the toe. At this time the sole wrap yarns are released through the use of the devices disclosed in said Oberholtzer application.

The upper end of the rod 102 is provided with a fixed collar 156 and slidably arranged on the rod 102 is a collar 158, there being between these collars a cushioning spring 160 surrounding the rod 102. Arranged to act beneath the collar 158 is a lever 162 pivoted at 164 to a post carried by the bracket 139 and arranged to be acted on at a pivot pin 166 by a rod 168 pivoted to a lever 170 which, in turn, is pivoted on the bracket 122. The lever 170, when the parts are in normal operating position overlies the upper end of a guided push rod 172 which is moved upwardly by the action of cams on the main cam drum of the machine. A latch 151 urged by a spring 153 toward a stop 155 is provided with a hook 157 which is arranged to engage a pin 159 carried by the bracket 128 to latch the wrap assembly in its lower active position. A pulley 161 carried by the tube 118 supports a cable 163, one end of which is secured to a counterweight 165 while the other end is secured through a pin 167 to a sliding sleeve 169. The pin 167 projects inwardly through a longitudinal slot 171 in post 118 and underlies the lower end of tube 120. The counterweight is so chosen as to substantially balance the weight of the wrapping assembly so that upon release of the latch 151 this may be easily moved upwardly and swung laterally to a convenient position for access to the lower ends of the wrap yarn carriers. When it is desired to restore the wrap head assembly to active position it is moved back into alignment with the bearing 101 and is lowered thereinto, the cone 134 entering the tube 136 to provide accurate alignment and rigidity. The latch 151 then engages the pin 159 to hold the assembly in operative position.

The lower end of the stationary cylinder 100 carries through an extension 184 a wrap horn indicated generally at 186 which at its initial end is in the form of a horizontal strip 188 and which beyond the region of presentation of wrap yarns to the needles has a raised extension 190 which insures a high position of the wrap yarns on the needles as they are raised following wrapping. The trailing end of this horn terminates as a wire 192 which overlaps the sloping end 194 of the wrap horn with clearance in the region of the downwardly and outwardly sloping face 195 of this portion of the wrap horn. The lower edge of the wrap horn is relieved at 196 for a purpose hereafter pointed out.

Referring now to Figures 5, 6 and 7 there may be described those cams which, by acting upon the butts 73 of the jacks 72, serve to project the wrap yarn carriers across the needle circle. These cams comprise cams 200, 202 and 204 which operate at the first wrap position and cams 210, 212 and 214 which operate at the second wrap position. The cams 200, 202 and 204 are pivoted on a common stud 206 and are urged outwardly by individual springs 208. The cams 210, 212 and 214 are pivoted on a common stud 215 and are urged outwardly by individual springs 216. Each of the cams 200, 202 and 204 is provided with a back portion 218. Individual operators are provided for each of these cams which are identical so that one only need be described. This comprises an adjustable screw 220 carried by a lever 222 pivoted on a stud 224 and urged in a counterclockwise direction as viewed in plan by a spring 226 against a stop pin 223. A Bowden wire 230 connected to an individual push rod serves to move the lever 222 in a clockwise direction with the result that when no cam on the main cam drum acts on a push rod the screw 220 engaging a high part of the portion 218 of the corresponding cam will hold the cam in its innermost active position. When the push rod is raised by a cam on the main cam drum the screw 220 moves toward the left in Figure 5 and so releases the corresponding cam to render it inactive. The cams are thus rendered individually controllable through their corresponding push rods and Bowden wires.

The cams at the second wrap position are also individually controlled by a somewhat different mechanism. A housing 232 is provided to mount a series of slides 234 each of which is provided with a projection 236 co-operating with a projection 238 on the corresponding cam

15 of this second group. The slides are normally urged downwardly as viewed in Figure 5 by individual springs 240 and are adapted to be pulled against the action of these springs by individual Bowden wires 242 connecting 20 to corresponding plungers acted upon by cams on the main cam drum. When any plunger is not acted upon by its cam its slide will be retracted by its spring 240 and the corresponding cam will be held in operative position. When drum cams act on a plunger its slide will be pulled to a position to permit withdrawal of its cam by its spring 216 to an inoperative position. Individual screws 244 serve to adjust the slides 234 in a direction toward or from the axis of the needle cylinders so as to provide adjustment of the operative positions of the 25 cams.

Reference may now be made to Figures 3 and 4 for the assembly which includes the cams 260, 262 and 264 which, by action on the butts 84 of the wrap yarn carriers, serve to move them inwardly of the needle circle 20 and, as will be pointed out hereafter, also serve to limit the outward movements of the wrap yarn carriers. The main supporting bracket 103 which mounts the bearing 101 for the rotating supporting head of the wrap yarn carriers serves for the mounting of a member 246 which 25 supports the tube 100 for accurate positioning as to its angular circumferential position, as to its height, and also as to its tilt relationship to the axis of the needle cylinders. To achieve this screws 248 pass through circumferentially extending slots 250 in the bracket 103 and are threaded into the member 246. Other screws 252 are threaded into tapped openings in the bracket 103 and their lower ends bear upon the upper surface of the member 246. As will be evident, this arrangement of the screws permits substantially universal adjustment, 30 within limits, of the position of the member 246 and the tube 100 which it carries, the screws being tightened when the tube 100 is in properly adjusted position. This adjustment is rather critical and is for the purpose of insuring proper relationship to the needles of the wrap 35 horn carried at the lower end of the tube 100.

Secured to the upper surface of the bracket 103 by screws 256 is a plate 254, through circumferential slots 258 in which the screws extend. This plate 254 serves as a mounting for the cams 200, 202, 204 and 210, 212 40 and 214 previously described, and their operating elements, and also for the cams 260, 262 and 264. Additionally supported by this plate are a pair of yield cams 266 and 272. The first of these is pivoted at 268 and urged in a clockwise direction as viewed in Figures 3 and 25 50 by a spring 270, while the second is pivoted at 274 and is urged clockwise by a spring 276.

At this point there may be described with reference to Figures 22 to 28, inclusive, as well as to Figures 3 to 7, inclusive, the details of operation of the wrap yarn carriers involved in the production of wrapping. A typical arrangement of the butts 73 of the jacks 72 and of the butts 84 of the wrap yarn carriers, and the various cams which operate on these butts, will be described. 55 As will be evident, the arrangements about to be described are subject to rather arbitrary choice but to provide consistent detailed description a particular arrangement is illustrated and described.

From Figure 1 it will be noted that there are provided eight levels of butts 73 on the jacks 72. On the present machine only the six lower levels are used, the two uppermost levels being provided for more elaborate or special patterning in which case there would be added two more cams to the set of six illustrated in Figure 7.

Referring now to Figure 24, there are diagrammed 70 therein six typical wrap yarn carriers which are associated in pairs, the members of each pair being of the types 64 and 64' previously referred to mounted in a common slot 80 and associated with a common disc 93 whereby the carriers of the pair are limited in their relative movements. In the diagram of Figure 24 it is assumed that the wrap yarn carriers are moving toward the left past the controlling cams, this movement corresponding to a counterclockwise rotation of the needle cylinders and the wrap assembly. The wrap yarn carrier W₁ is 75 of the type 64' and is arranged to wrap wide panels at the first wrap position while the carrier W₂ is of the type 64 and is arranged to wrap wide panels at the second wrap position. The carrier W₁ of the type 64' is arranged to wrap narrow panels at the first wrap position on 80 needles of the instep series while the carrier W₂ is ar-

ranged to wrap narrow panels at the second wrap position on needles of the instep series. The carrier S_1 is arranged to wrap narrow panels at the first wrap position on needles of the sole series and the carrier S_2 is arranged to wrap narrow panels at the second wrap position on needles of the sole series. The butts 73 of the jacks corresponding to these carriers are shaded and are indicated at levels designated by numerals corresponding to the cams shown in Figure 7 followed by the letter A. As will be noted from Figure 7, the cams 200 and 210, which from Figure 24 will be seen to act upon the butts 73 corresponding to those carriers which wrap wide panels, are somewhat longer than the other projecting cams of the groups acting on butts 73. They serve to hold outwardly the wide wrapping carriers through a greater angular extent of movement of the needles than is the case of the other cams which cooperate with the carriers wrapping narrow panels.

The butts 84 of the wrap yarn carriers are arranged as in the lower portion of Figure 24, the levels of which are designated by numerals corresponding to the return cams 260, 262 and 264 followed by the letter A. Each of the wrap yarn carriers W_1 has a single butt at the level 262A while each of the wrap yarn carriers W_2 has a single butt at the level 264A. Each of the wrap yarn carriers of the type I_1 or S_1 has a pair of butts 84 at the levels 260A and 262A. Each of the wrap yarn carriers of the type I_2 or S_2 has a pair of butts 84 at the levels 260A and 264A.

Referring now to Figures 25 to 28, inclusive, the first of these illustrates the various cams viewed from a level above the yield cams 266 and 272 which are at a common level to act upon shoulders 277 of the wrap yarn carriers. Figure 26 is viewed from a level below the yield cams but above the cams 260₁ and 260₂ which collectively constitute the cam generally designated heretofore as 260. Figure 27 is viewed from a level below the cams 260 but above the cams 262₁ and 262₂ which collectively constitute the cams 262 previously described. Figure 28 is viewed from still another level below the cam 262₁ and illustrates the cams 264, cams 262₂ being also active at this level and shown in section.

Reference will first be made to the sequence of operations involved in wrapping by means of the wrap yarn carriers W_1 and W_2 to wrap wide panels. As they approach the first wrap position the butt 84 of a wrap yarn carrier W_1 moving at the level 262A will be engaged by the cam 262₂ with the result that the carrier W_1 will be in its extreme inner position. At the same time the butt 84 of carrier W_2 moving at the level 264A will be engaged by the cam 262₂ so that this carrier will also be in its extreme inner position. The paths of the butts just mentioned are indicated in Figures 27 and 28, respectively, at 262A and 264A, these paths being indicated as slightly inward of the actual paths of the outer edges of the butts for clarity of illustration.

As the first wrap position is approached the cam 200 acts upon the jack butt 73 of the carrier W_1 which is located at the level 200A. This cam will serve to rock outwardly the lower end of carrier W_1 , the outward movement being restrained by the action of the yield cam 266 on the shoulder 277 of this carrier. As will be noted from Figure 27, the continuity of the cams at the level 262A is interrupted at the first wrap position so that no cam at this level will restrict the outward movement of the lower end of the carrier W_1 . However, at the level 264A there is provided the cam 264 at the first wrap position which will limit the outward movement of the butt 84 of the carrier W_2 associated with W_1 . Since the outward movement of the carrier W_2 is thus limited the outward movement of the carrier W_1 will also be limited by reason of the presence of the disc 93 projecting through the holes in the two carriers. The adjustment of the cam 200 is such, of course, as to avoid undue strain in attempting to force the carrier W_1 outwardly beyond its limited position. The construction, however, is such that the position of the lower end of carrier W_1 is definitely determined, overthrow being positively limited by the action of the cam 264. Immediately after the wrap yarn carrier W_1 is fully projected outwardly it will be engaged by the abutment 580, hereafter described, at the first wrap point and will be retarded to effect its movement relative to the needles to produce wrapping of its

wrap yarn about those needles which have been selected upwardly for wrapping.

When the butt 84 of carrier W_1 approaches the cam 262₁ its jack butt 73 will be released by the cam 200 and the action of the cam 262₁ will move the lower end of the carrier W_1 inwardly as indicated in Figure 27. It may be noted that the innermost position of the edge of the cam 262₁ is not as far inwardly as the active edge of the cam 262₂.

As the butt 84 of the carrier W_2 moving at the level 264A clears the end of the cam 264 the cam 210 will act upon the butt 73 of the jack associated with the carrier W_2 and will project the lower end of this carrier outwardly, the outward movement being restrained by the yield cam 272 acting on the shoulder 277 of the carrier W_2 . The outward movement of this carrier W_2 is also limited, in this case by the limit of the outward movement of the butt 84 of the carrier W_1 by the cam 262₁, the restraint being effected through the interconnection of the two carriers by their common disc 93. When the carrier W_2 is fully projected it will engage the abutment 588 at the second wrap point and will be restrained so that it will move relatively to the needles which have been selected upwardly for wrapping at this second wrap point. Its wrap yarn will be thereby introduced to the needles to effect a wrapping operation.

The next event involving carriers W_1 and W_2 is their complete inward return movement effected by the action of the cam 262₂, following release of the carrier W_2 by the cam 210.

In summary of the above it will be noted that the two associated carriers are successively moved outwardly with restraint of each being effected by the action of a cam on the other and that in the case of these carriers the outer position is of long duration as determined by the elongated forms of the cams 200 and 210 and delay of return actions by the cams 262₁ and 262₂.

The controlling actions of these carriers designed to wrap short panels, i. e., the carriers I_1 , I_2 , S_1 and S_2 , are quite similar except that, as will be evident from Figure 26, the return actions are now controlled by the cams 260₁ and 260₂ acting upon the butts 84 which move at the level 260A their paths being correspondingly designated in Figure 26. The returns of the wrap fingers are accelerated and these accelerated returns are permitted by the shorter lengths of the cams 202, 204, 212 and 214. The paths involved will be evident from Figure 26. It will be clear that the projection of the lower ends of these wrap yarn carriers will be restrained by the yield cams 266 and 272 and will be limited by the actions of the cams 264 and 262₁ as in the case of the previous description of the operation of the carriers for wrapping wide panels.

As will be evident, while the foregoing description has implied wrapping by both associated carriers of a pair it will be evident that one or the other need not wrap and, of course, need not carry a wrap yarn. However, both carriers enter into the control of each since the inactive carrier is arranged to limit the outward movement of the active carrier. If a carrier is to be inactive it may be replaced by a dummy carrier essentially the same as an active carrier so far as its butt arrangement is concerned but differing therefrom in having its lower extended portion removed. These dummy carriers which cooperate in limiting the outward movements of active carriers should, of course, be distinguished from a dummy spacer such as 65 which serves no purpose except that of maintaining proper tension on the spring bands 66 and 82.

Figures 8 to 12, inclusive, illustrate the devices involved in selection of needles. The cam 278 which is carried by the upper needle cylinder is arranged to engage the roller 280 carried by bell crank 282, an adjustable screw 284 in which engages a wear plate 286 carried by an arm 288 mounted on an upright shaft 292 having suitable bearings in the machine frame. A spring 290 maintains the screw 284 in contact with the plate 286. At its lower end the shaft 292 is provided with an arm 294 to which is pivoted at 295 a link 296 the other end of which is pivoted at 297 to a racking plate 298. This, in turn, is pivoted at 299 to a second link 304 which is pivoted at 305 to a second racking plate 306. The racking plate 298 is pivoted on the trick wheel 300 which is eccentrically mounted in the frame to per-

mit adjustment of the trick wheel toward and from the lower cylinder. The racking plate 306 is similarly mounted on the second trick wheel 308. The eccentric mounting of the shaft 346 is illustrated in Figure 9 where it is shown as provided with a pair of eccentric extensions 344, the lower of which may be clamped in angularly adjusted position by a screw 345. The arrangement of the shaft 302 is similar to the arrangement of shaft 346. The pivot screws 297, 299 and 305 are also preferably eccentric to provide accurate adjustment of the racking plates with respect to the trick wheels driven thereby.

The link 304 is urged by a strong spring 310 toward the left in Figure 8, which spring acts through all of the connected elements and serves to move the roller 280 toward and against the cam 278.

Associated with the link 296 is a plate 312 which is pivoted on the pin 295. This plate is provided with a slot 314 the upper end of which as viewed in Figure 8 is normally held in engagement with a pin 316 carried by the link 296 under the action of a spring 318. The member 312 is provided with a notch 320 with which is arranged to cooperate a pin 322 carried by a lever 324 which is mounted on a fixed pivot pin 323. A spring 325 normally urges the lever 324 in a clockwise direction to move a follower end 328 toward the butts of tricks carried by the trick wheel 309. Movement of lever 324 is limited by an eccentric stop 327. A Bowden wire 326 is provided to move the lever 324 against the action of spring 325 when a plunger to which the Bowden wire is connected is raised by cams on the main cam drum of the machine.

The racking plate 298 has pivoted to it at 332 a racking pawl 330 controlled by a spring 334 and arranged to advance the trick wheel 300 step by step by engagement with ratchet teeth 336 on the trick wheel. A similar pawl 338 is pivoted at 340 to the racking plate 306 and is controlled by the action of the spring 342 to provide step by step advance of the trick wheel 308 by engagement with the ratchet thereon. The trick wheel 308 is provided with a downwardly extending hub 348 which surrounds the shaft 346 and this is, in turn, surrounded by a member 350 which has frictional engagement with the hub by reason of the provision of a friction shoe 352 urged inwardly by a spring 354 carried by the member 350. A pin 356 extending from the member 350 is guided for vertical movement but restrained against angular movement by a hook member 360 carried by an adjustable plate 362 which confines the pin 356 against a vertical wall on the frame. Extending downwardly from the member 350 is an adjustable follower screw 364 having a conical head which is engageable by a lever 366 provided with a pair of cam steps 368 and 370. The lever 366 is pivoted to the frame at 372 and is urged in a clockwise direction by a spring 374. The lever 366 is under control of a Bowden wire 376 which is connected to a plunger arranged to be acted upon by cams on the main cam drum of the machine. Various of the plungers now being referred to, some of which were referred to previously and some of which will be referred to hereafter, are illustrated at the right hand end of Figure 8.

The various parts which have been detailed with respect to trick wheel 308 are also provided in association with the trick wheel 300 and need not be specifically described with reference to that trick wheel. A lever 330 which is similar to the lever 366 is pivoted at 382 and associated with the trick wheel 300, this lever 380 being acted upon by a spring 384 and the Bowden wire 386. Through the medium of the levers 366 and 380 the trick wheels may be caused to assume selectively three vertical positions so that butts on the trick wheel at three different levels may be brought into alignment with follower levers. This arrangement is such that a repetition of pattern control amounting to slightly less than three complete revolutions of the trick wheels may be provided. Alternately, of course, the trick wheels may be set up with two or three independent patterns thereon. By selection of the height of the trick wheels it will be evident that various elaborate patterning possibilities exist.

Associated with the trick wheel 308 are reading levers 388 provided with reading ends 390 arranged to follow the butts on the tricks. Individual springs 394 urge these levers toward the tricks. The levers are pivoted on a vertical pin 392 and are held properly spaced by spacers

on this pin and by a slotted spacer post indicated at 396. The ends of the levers 388 engage slides 398 provided with cam ends 400 which are adapted to act on the teeth of saw tooth sliders 402, one of these being illustrated in Figure 12. A stop post 404 limits the movements of the reading levers 388 toward the trick butts.

A lever 406 which is also pivoted on the pin 392 has its end arranged to engage the upright end 408 of an aligning cam slide 410 which is guided for horizontal movement by engagement of screws 412 threaded into the frame through horizontal slots in the slide. A spring 416 urges the slide 410 towards the lower needle cylinder to a position limited by an adjustable eccentric stop 414. The slide 410 has a vertical cam surface 418 which, by engagement with the outer ends of the slider butts, insures that the lower ends of the sliders are seated radially inwardly in the cylinder slots so that the sides of the sliders inwardly of the roots of the butts will not strike the cam ends 400 of the slides 398.

20 A lever 422 pivoted on an upright pin 424 is provided with tooth members 426 which may be selectively broken away if desired, these tooth members being at the levels of the reading levers 388 and arranged to engage the reading levers when a pull is exerted on Bowden wire 430 to remove them from engagement with the trick butts. The Bowden wire 430 is connected to one of the upright plungers following cams on the main cam drum. An adjustable screw 428 is arranged to engage under similar circumstances the lever 406 to retract the aligning cam slide 410 to an inactive position.

25 A set of reading levers 432 similar to the set 388 are mounted on the pin 323 and are provided with follower ends 434 engageable with the butts on the tricks in the trick wheel 300. Individual springs 436 urge these reading levers toward reading positions. These levers are stacked and spaced in the same fashion as the levers 388 at levels at intervals corresponding to the level of each third butt on the tricks. The ends of the levers 432 engage slides 438 which are provided with cam ends 440 arranged to engage the saw teeth on the saw tooth sliders.

30 A lever 442 corresponds to lever 406 and is arranged to engage a slide 446 which is provided with a cam end 448, this slide being identical with the slide 410 and being similarly mounted. A spring 450 normally urges this slide 446 toward the lower needle cylinder.

35 A lever 452 is pivoted on a pin 464 and is provided with teeth 454 which are at the level of the reading levers 432 and are adapted to move them out of action when the lever 452 is pulled against the action of spring 470 by the Bowden wire 456 which is connected to a plunger following cams on the main cam drum. Another lever 458 is mounted on the pin 464 and is provided with teeth 460 which are also arranged to engage levers 432 to move them out of action when the lever 458 is pulled against the action of spring 461 by Bowden wire 468 which is connected to a plunger following cams on the main pattern drum of the machine. It will be noted that the levers 452 and 458 are capable of independently removing the various reading levers from action depending upon the arrangement of the teeth 454 and 460 thereon. The particular use of these levers is subject to wide variation and, for example, the lever 452 may be arranged to control the arrangement of clocks while the lever 458 may control a pattern extending through the entire leg and instep of a stocking. In this last case an upward extension 462 of the lever 458 is arranged to engage the lever 442 so that the slide 446 may be pulled outwardly whenever the lever 458 is rocked to disengage 40 reading levers from the trick wheel 300. It will be evident that more than one lever 422 and more than two levers 452 and 458 may be provided if desired in order to secure still greater selective control of the groups of reading levers.

45 Figures 13 and 14 show a safety mechanism which is arranged to prevent a press-off when making plain socks without transfer of needles to the upper cylinder as is commonly done when machines which are normally operated to involve transfer of needles are being tested or fixed. When this type of operation is desired it is customary to render the lower transfer bolt cam inactive so that needles are retained in the lower cylinder rather than transferred as would normally be the case. Under these circumstances, if the machine is operated with the usual cam arrangement to produce a press-off draw thread

the press-off bolt cam would be rendered operative in the cycle and consequently press-off would occur from all of the needles then in the lower cylinder. The Bowden wire 472 shown in Figure 14 is the wire which renders the press-off bolt cam active. Heretofore, this was connected directly to the plunger or push rod 476 following cams on the main cam drum. In the present machine there is provided a sliding casting 474 on the plunger 476 to which casting the Bowden wire 472 is attached. A strong spring 480 pulls this casting upwardly against a pin 478 passing through the plunger 476, the upper end of the spring being anchored to an adjustable collar 482 at the top of the plunger. This spring 480 is so strong that unless the casting 474 is restrained, the casting and plunger 476 will normally act as a single connected unit to operate the Bowden wire 472.

The plunger of the lower transfer bolt cam is indicated at 484 and this is normally acted upon by a lever 486 which is pivoted on a post 488 and is moved against the action of a spring 504 by a toggle link 490, the upper end of which engages in a socket 492 in the lever 486 while its lower end is pivoted at 494 to a collar 496 clamped on a plunger 498 operated on by cams on the main cam drum. The collar 496 may be finely adjusted and then clamped in position through the use of a screw 500 which bears on a fixed collar 502 also carried by the plunger 498.

The lever 486 carries an extension 506 provided with a laterally turned end 508. When the toggle 490 is in operative position so that rise of the plunger 498 will swing the lever 486 to introduce the lower transfer cam, the end 508 is swung out of the path of the casting 474 so that when the plunger 476 is raised the Bowden wire 472 will be operated in the usual fashion to put the press-off bolt cam in operation. As will appear hereafter, under these conditions a press-off draw thread is formed. The spring 480 is much stronger than the resistance encountered by the Bowden wire 472 and consequently the latter acts as if rigidly connected to the plunger 476.

On the other hand, if the toggle 490 is removed from the socket 492 so that the lower transfer cam remains withdrawn despite rise of the plunger 498, the end 508 will overlie the casting 474 so that even though the plunger 476 is raised by a cam on the main cam drum the Bowden wire will not be pulled, the spring 480 yielding to permit the casting 474 to remain stationary.

The yielding connection provided by spring 480 has a further function of permitting the main drum to be racked by hand even though butts may be directly inside the press-off bolt cam 643. This is often done if something happens to the machine during knitting of a sock. After fixing the trouble, the main drum and the chain are both moved to starting position and a new sock is immediately started rather than waste time and yarn in finishing a sock already spoiled. If any butt is behind bolt cam 643, the spring merely yields while a drum cam is passing under the plunger 476.

It is desirable to provide for the simultaneous interruption of all wrapping at certain times by rendering cams 200, 202, 204, 210, 212 and 214 inoperative to act on jacks 72 and by removing from action the reading levers 388 and 432 and the slides 410 and 446, this last being effected by the rocking of levers 422, 452 and 458. As will have been noted from the previous description, pulls on Bowden wires render all of these elements inoperative. To accomplish this end a hand throw-out mechanism is provided as illustrated in Figures 15, 16 and 17. In these figures there are illustrated various plungers normally adapted to be acted upon in selective fashion by cams on the main cam drum of the machine. Such plungers are illustrated at 510, 522 and 528. The plunger 510 is provided with an arm 514 connected to a Bowden wire 516 and an arm 518 connected to a Bowden wire 520. For elaborate clocking control still more Bowden wires may be attached to this plunger 510. Plunger 522 is connected through an arm 524 to a Bowden wire 526. Plunger 528 is connected through an arm 530 to a Bowden wire 532. As will be evident, additional Bowden wires may be connected to any or all of these plungers and, in fact, additional plungers may be grouped with these. The Bowden wires just mentioned may be identified with various Bowden wires such as 230, 242, 430, 456 and 468 previously mentioned, the particular correspondence of the Bowden wires being subject to rather arbitrary choice depending upon the

types of patterns which are desired. In any event, provision is made, as will be now indicated, for the simultaneous exertion on these Bowden wires of pulls to the limits which would be imposed on them by cams on the main cam drum.

A block 540 is slidably mounted on the plunger 510 and extends between the plungers 522 and 528 to be slidably guided thereby. Above the block 540 the plungers are provided with collars 534, 536 and 538 all of which overlie the block 540. Pivoted to the block 540 at 542 is a lever 544 having a nose 546 at its lower end engaging a hardened wear plate 548 carried by the machine frame. When the lever 544 is in the full line position illustrated in Figure 15 the block 540 remains down and imposes no restraint on the normal operation of the plungers by their cams. However, if it is manually pulled to the position illustrated in construction lines in Figure 15 the nose 546 will move toward the left to the position 546' slightly to the left of the pivot 542 which is raised with the block 540 which, in turn, raises all the plungers to heights at least as great as those to which the cams on the main cam drum would raise them. The result is that all of the elements controlling wrapping will be rendered inoperative irrespective of the cams on the main cam drum. The racking of the pattern drums is not interfered with however. An example of the use of this throw-out mechanism would be that arising if a wrap yarn was broken because of a knot or some other cause. By pulling on the lever 544 the cams are withdrawn from the butts 73 on the jacks 72 and the wrap head may then be unlatched and raised so that the wrap yarn carrier may be rethreaded and the head replaced, all in a very short time so that knitting may be resumed immediately after moving the lever 544 to its inoperative position.

Referring now to Figures 18 and 19 there are illustrated therein the devices constituting a slider controlled stop motion. A member 550 carries a detector 552 in the form of a small, flat plate having a projection which on one side provides an abrupt shoulder 554 and on the other side a sloping cam edge 556. This detector projection has the position illustrated in the cam development Figure 29. It is located just above the level of the tops of sliders which are moving at welt level and circumferentially is located directly above the lower end of the run-down stitch cam. It is accordingly in position to be engaged and moved toward the left in Figure 18 by any slider which has not been pulled to welt level or below in a run-down direction. The member 550 is provided with a slot 558 which embraces a pin provided with a shouldered spacer 560 to hold the detector at the proper level. A notch 562 normally embraces a pin provided with a spacer 564. A rod 566 is linked to the left hand end of the member 550 as viewed in Figure 18 and is guided in a bracket 570, a compression spring 568 reacting between this bracket 570 and a shoulder on the rod 566. The arrangement is such as to hold the member 550 in a clockwise position limited by engagement of the trough of the notch 562 with its pin. A shoulder 572 on the member 550 engages a pin 574 projecting downwardly from an arm 576 carried by the shaft 577 which supports the conventional stop motion detector 578 which is arranged to detect the piling up of yarn in a needle hook or bent or flying latches as in press-off or the like. The shaft 577 operates the usual stop motion which is well known and need not be described in detail. The usual stop motion spring applied to this shaft urges it in counterclockwise direction so that the pin 574 normally maintains the member 550 in a right hand position limited by engagement of the left hand end of slot 558 with the pin passing therethrough. As will be evident this arrangement is such that a slider moving too high in the run-down direction will engage the shoulder 554 and by moving member 550 to the left will trip the stop motion. On the other hand, during a reverse stroke during reciprocatory knitting a slider will engage the cam edge 556 and merely rock the member 550 counterclockwise against the action of spring 568 without causing any tripping action.

During gore knitting, however, certain of the sliders will be raised out of action to the so-called heel level and if special provision were not made these sliders would trip the stop motion. Accordingly, the gore sliders are provided with a slot 11 as indicated in Figure 29, which, when they are riding at heel level, will be lined up with

the detector 552. The slots may accordingly pass the detector without tripping action. However, since only the sliders in the gore sections have such a slot, if anything should happen so that more sliders are raised to heel height (for example, a jam or break of the main chain) the machine would be immediately stopped.

Also illustrated in Figure 18 are the wrap finger abutment 580 at the first wrap position and the wrap finger abutment 588 at the second wrap position. The former is carried by a bell crank 582 pivoted on a stud 584 supported on a fixed bracket 606. An adjustable screw 586 carried by the bell crank abuts a pad on a bracket to limit counterclockwise movement of the abutment. The abutment 588 is carried by a lever 590 pivoted on a fixed pin 592 which carries a bracket 593. A screw 594 carried by this bracket limits counterclockwise movement of this abutment by engaging its outwardly projecting portion. A spring 596 tensioned between the abutments normally maintains them in their counterclockwise limited positions but permits either of them to yield in a clockwise direction to prevent breakage if for some reason normal deflection of a wrap yarn carrier by them is prevented. Ordinarily, in normal operation, they present fixed abutments for the wrap yarn carriers.

Also illustrated in Figures 18 and 19 is the assembly of the latch opener 598, the needle leveler blade 614, and the press-off bolt cam, the housing of which is indicated at 640. The latch opener 598 is carried by the member 600 which is pivoted on a shoulder screw carried by the bracket 606. A spring 608 urges the member 600 in a counterclockwise direction to bring its tail 602 into engagement with the adjustable stop screw 604 which serves for fine adjustment to locate the pointed end of the latch opener 598 in proper relationship with the needle latches. A rod 610 extends laterally from the member 600 and serves for its control as later described.

The needle leveler blade 614 is adjustably carried through the medium of screw and slot connections illustrated at 616 by a lever 618 which is pivoted on a screw 620 carried by the bracket 606. A post 622 carried by this lever is provided with a stop screw 624 which is arranged to engage an abutment surface on the bracket 606 to limit counterclockwise movement of the blade 614 which, by adjustment of the screw 624, may be accurately positioned with respect to the needle circle. A spring 626 urges the lever counterclockwise, this spring being anchored to the hub of a lever 628, the arm 630 of which is arranged to be engageable with the post 622. The lever 628 is carried by a shaft 632 which at the lower side of the bracket 606 carries the bell crank 634 which is arranged to be acted upon by the Bowden wire 472 previously described and illustrated in Figure 14. The bell crank 634 carries an adjustable screw 636 which acts upon the plunger 638 of the draw thread bolt cam contained in the conventional cam housing 640 which contains a spring urging the plunger 638 outwardly and consequently urging the bell crank 634 in a clockwise direction. The bell crank 634 also carries a rod 642 having an upwardly turned end which is arranged for engagement with the rod 610 previously mentioned. A spring 641 acting between the rod 642 and a fixed anchor on the frame serves additionally to urge the bell crank 634 in a clockwise direction.

The bolt cam at 643 is arranged to be stepped into action and also to be stepped out of action, under some conditions missing short butts of sliders in the lower cylinder while engaging long butts. The needle leveler blade 614 and the latch opener 598 are so interconnected with the bell crank 634, however, that they are in active position even when the bolt cam may engage only long butts. Assuming, for example, that the Bowden wire 472 is released so that the bell crank 634 occupies an extreme clockwise position, the action of the arm 630 will hold the needle leveler blade 614 retracted and the rod 642 will hold the latch opener 598 retracted. When the Bowden wire 472 is pulled, however, to an extent sufficient to move the bolt cam inwardly to engage only long butts the arm 630 will be sufficiently retracted to permit the blade 614 to move into active position limited by the adjustment of screw 624. At the same time the rod 642 will have released the arm 610 so that the tail 602 of the latch opener carrier will engage the stop screw 604. Further counterclockwise movement of the bell crank 634 will be without further action on the needle leveler and latch opener. The particular nature of cooperation

between the needle leveler blade 614 and the latch opener 598 and the needles need not be described herein since it is identical with what is described in the application of Albert L. Oberholtzer, Serial Number 690,671, filed 5 August 15, 1946, now Patent No. 2,557,137. The action will, however, be briefly pointed out in the description of the operation of the machine to form a press-off draw thread.

The general operation of the machine may be best described with particular reference to Figure 29 which illustrates the various cams for controlling the rotating instrumentalities. Various of these cams have been heretofore described while those which have not been referred to correspond generally in their construction and functions to cams commonly provided in this general type of machine. 485 is the lower transfer bolt cam which has been referred to as controlled by the plunger 484 in Figures 13 and 14. The press-off bolt cam 643 is the cam contained in the housing 640 illustrated in Figure 18. The lower cylinder forward stitch cam 650 is mounted in usual fashion for radial adjustment and also together with reverse stitch cam 652 and the lower cam 655 for axial adjustment to control the lengths of stitches drawn by needles operating in the lower cylinder. With these cams there is associated the center cam 654.

The race 656 is followed by the butts 26 and 28 of the sliding walls 22 and 24. At 657 this race acts on the outer edges of the butts 26 and 28 to prevent the sliding walls from being pulled out as the sliders are tilted during transfer actions. The cam 658 is adapted to be moved upwardly during knitting of heels and toes to avoid straining stitches which were drawn in the upper cylinder.

The upper cylinder stitch cam 660 and associated cam 662 are axially adjustable for control of stitch length. Cams 666, 668, 670, 672, 485, 650, 643, 674, 676 and 678 are radially adjustable and have functions which will be hereafter described. A switch cam 664 is axially movable to restore needles to clearing level after the formation of heels and toes. Cams 680 and 682 are provided to act on butts of sliders at clearing level to provide space for the location of the picker 684 when it is held down temporarily as will be mentioned hereafter. The usual raising pickers are provided at 686 and 688.

The operation of the machine may be best started with consideration of the formation of looper's rounds which constitute the completion of a stocking after the formation of its toe. In this operation all the needles are carried by lower cylinder sliders and the sliders are rotating so as to carry the various elements through the cams from the right to the left of Figure 29. The transfer bolt cam 666 and the welt bolt cam 672 are inactive in the upper cylinder cam section causing the sliders in the upper cylinder to follow a normal knitting race. In the lower cylinder cam section the run down or forward stitch cam 650 is in action and the welt bolt cam 678 is also in action so that all of the needles knit plain stitches in the lower cylinder, drawing yarn from a yarn feed finger in the position 645. It will, of course, be clear that as is conventional this machine is provided with a plurality of yarn feeding fingers acting at a single feed point, which fingers may be selectively brought into and taken out of action to provide desired main yarn changes.

Following the formation of the looper's rounds transfer of alternate needles to the upper cylinder is accomplished in conventional fashion by the action on suitable long and medium transfer butts of the lower cylinder sliders by the lower transfer cam 485. The division of needles thus provided effects the knitting of 1 x 1 rib fabric.

After the transfer to the 1 x 1 condition of the needles the welt is made for the press-off draw thread locking courses. The upper welt bolt cam 670 is stepped out, as the long butts are passing to clear short butts, and as the short butts are passing it is pulled all the way out, leaving the upper cylinder sliders in the welt race at constant level with their knitting butts passing over the top of the stitch cam 660. In the meantime the alternate needles carried by the lower cylinder sliders continue to knit plain fabric. After about three and one-half such courses of knitting a change is made to produce the loose or pull courses for the press-off draw thread.

To effect this result the upper welt bolt cam 670 is stepped back into action, first against the short butts as they are passing and then fully inwardly as the long butts

pass this cam, to resume 1 x 1 rib knitting on the needles engaged by the upper cylinder sliders. The clearing bolt cam 674 and the press-off bolt cam 643 are now additionally brought into action to act on the lower cylinder sliders. Concurrently with the bringing into action of the cam 643 the latch opener 598 and needle leveler blade 614 are moved into action. The latch opening occurs as the needles rise over the bolt cam 678. While the needles carried by both top and bottom cylinder sliders now draw yarn at the main yarn feed the lower cylinder sliders pass down the stitch cam 650 but then rise over the cam 674 and cam 675 to clear their stitches, shedding the stitches as they pass under the press-off bolt cam 643, leaving only the rib needles with loops. The fabric take-up plus the toe pocket weight elongates the rib loops by pulling the extra length of yarn drawn by the needles controlled by the lower cylinder sliders.

After, for example, three and one-half courses of the foregoing the cams 670, 674 and 643 are stepped out and welt knitting is resumed in the fashion previously described. When sufficient welt courses are formed the bolt cam 670 is again stepped into action and the knitting of 1 x 1 rib fabric is resumed.

When enough fabric has been knitted for the formation of a desired 1 x 1 rib top the transfer cams 485 and 666 are introduced to act on the transfer butts of the sliders in the usual way to change from a 1 x 1 set up of the needles to the desired set up or distribution of the needles for production of the desired broad rib structure of the leg of the stocking. This, for example, may involve a 7 x 3 arrangement with a plain panel on each side, for example, seventeen needles wide, in which there may be wrapped two-color clock.

In the knitting of the leg cams 668 and 670 are in action while 672 is out of action with the result that the needles which are controlled by sliders in the upper cylinder take yarn from the main yarn finger at 645 and knit rib stitches. In connection with the lower cylinder the only radially movable cams which are in action are 650, 676 and 678. The cams 676 and 678 serve to level the saw tooth sliders for selection by the cams 400 and 440 under control of the trick wheels as previously described, the controls being now set to cause selection of these cams by the trick wheels. Cams 418 and 448 insure the alignment of the saw tooth butts of the sliders 402 so as to be properly engaged by the selecting cams. The selecting cams acting on the saw tooth butts raise the needles at the respective first and second wrap positions to present them at a level below clearing height for the reception, above uncleared old loops, of the wrap yarns which are caused to move relatively to the needles by the abutments in the fashion previously described. The wrap yarns are, of course, presented over the horn 188, the wrap yarns being raised by the rise in this horn at 190 to prevent their being cleared when the needles are raised by cam 679 to clear old loops and being finally shed over the wire extension at 192. The horn supports the wrap yarns and prevents them from descending with the needles during the needle lowering. The knitting butts of the lower sliders follow a path over the reverse stitch cam 652, down the center cam 654 and the forward stitch cam 650, the main yarn being thereby knit with the wrap yarn or yarns, are then raised slightly by cam 676 for alignment with the saw tooth selecting cams and whether they are raised or not by these are depressed by cam 677 to rise again over cam 678 to effect alignment with the saw tooth selecting cams 440 for the second wrapped portion. The knitting butts then rise over the cam 679, whereby the old loops are cleared without clearing the wrap yarns, to repeat the cycle.

The relation of movement of the needles selected for wrap by cams 400 and the movement of wrap yarn fingers is quite critical. Since the needles are floating, so to speak, in the slider hooks, it is vital that the needles rise high enough to turn their latches safely and insure the wrap yarn catching or passing below the needle hooks but not high enough to prevent the wrap finger from passing over the top of the needles after the finger is projected its full distance. Also the first wrap needle of the panel must be raised all the way up by a cam 400 before the wrap finger passes the needle in order to insure the wrap yarn covering the full panel since it may have been last knit by the last needle of the wrap panel. At the first wrap position the trailing finger is the one which passes the needle row, the leading finger being

carried along by the action of the disc 93. The yield cam 266 prevents the finger from jumping across the needle row due to impact with its projecting cam prior to the rise of the needle. All needles raised for wrap at the first wrap position are then lowered below the original level by the cam 677 after the wrap finger has been returned inside the needle row, but not necessarily to its inactive position, by a return cam. Cam 678 then levels off the sliders for selection by the cams 440. Needles raised by the cams 440 interlace the wrap yarn placed in the hooks of needles at the first position and are then wrapped by the leading finger. It can be readily understood that with the two yarns interlaced on the same panel of needles, the matter of drawing both yarns through to take up the slack at the end of the wrap horn is much more difficult than with a single yarn. With only one wrap position, only one wrap yarn would have to be controlled. This would slide easily through the interlaced needles and the timing or location of the end of the wrap horn could be placed so as to take out all the slack, the interlacing through the needles putting very little resistance on yarn drawn from the source of supply or on the yarn takeup. With two yarns interlaced on different needles in the same panel there is considerable resistance due to the wrap yarns crossing and re-crossing each other several times in the same panel, due to selection at the two wrap positions. Even in a narrow panel of five needles it may be that the yarns will cross each other four times; whereas, if only one yarn were used there would be very little interference to yarn movement through such a panel.

Another problem involved is that of protecting the wire 192 from the heel and toe pockets as they are being knit in reciprocation. A clearance 196 at the sinker knocking over position in run down direction is provided to assist in getting the puckered courses of the pockets under the lower portion of 188. It was also found necessary to have the outer edges of all angles of the plating cam and wrap horn to contact these puckered courses first thereby presenting a "camming in" effect to the fabric. A radius at 195 above the outer lower edge of the plating cam angle 194 provides both a clearance for the wrap yarns around the wire 192 and protection for the wire from the puckered fabric during reciprocation. Also, there must be enough clearance to knit loops without stripping all the supply through the panel again with the drag incurred. The wire 192 in the end of the wrap horn solves this problem nicely and at the same time leaves no surplus yarn across the back or inside of the wrapped panel. This wire sits relatively to the inside of the needles and as the wrap yarns hit the front angle 194 of the plating cam the excess yarn is drawn through the interlaced needles except for that portion from the last needle in the previous course to the first needle of the panel wrapped while the wire is still holding the yarn. As this passes off the wire the yarn then cams down and under the angle 194 of the plating cam. Since various wrap yarns and patterns require various adjustments of the plating cam and wire the bracket 246 is made adjustable both vertically and circumferentially through the medium of the screws 248 and 252 and slots 250.

The details of operation of the wrap yarn carriers have already been described as have also been the matters of shifting of the trick wheels axially to produce changes in the pattern controlled thereby and the matters of selectively discontinuing the controls of groups of selecting cams. The latter is particularly involved in the interruption of wrapping in the sole portions of stockings. Interruption of the wrap patterning during the formation of the heel is accomplished by preventing both projection of the wrap yarn carriers by rendering their projecting cams inoperative and by preventing selections of needles to wrap level by rendering the cams 400 and 440 inoperative. At the same time the advance of the trick wheels is interrupted by pulling the lever 324 to the upper dotted line position illustrated in Figure 8 by the action of a high cam on the main cam drum to move the pin 322 out of alignment with the slot 320 in the lever 312 thereby preventing return of the ratchet advancing pawls. During the formation of the toe similar interruption of wrapping may be accomplished but at this time or later the lever 324 may be released to provide retiming of the trick wheels effected by the dropping of the lever 324 to the lower dotted line position in Figure 8 when the follower of the lever 324 reaches a missing butt on one of the trick wheel elements. The details of knitting of heels and toes form no part of

the present invention but may be briefly described, reference being made to the application of Robert H. Lawson and Paul W. Bristow, Serial Number 728,226, filed February 13, 1947, in which details of the knitting of heels and toes are fully set forth.

At the time knitting of a heel is to be started the upper transfer cam 666 is inserted to transfer to the lower cylinder sliders all of the needles in the sole section. This action is effected in the usual fashion. Of the radially movable cams of the set cooperating with sliders in the upper cylinder only cam 672 is now active, this cam being in a position to engage only long knitting butts of upper sliders while missing short knitting butts. The short knitting butts occur in those sliders which control instep knitting while the long butts occur in the heel section of these sliders. Accordingly, the instep sliders in the upper cylinder will follow a path above the stitch cam 660 while the long butt sliders will follow a path below the stitch cam 660.

In the case of the cams associated with the lower cylinder only cams 650 and 674 are active and these are active only to operate on long knitting butts of the lower sliders. The short knitting butt sliders form the instep section and the long knitting butt sliders the heel section. Cam 664 occupies the upper construction line position illustrated in Figure 29. During the knitting of the heel the short butt lower sliders follow a path at welt level, avoiding depression by the cams 650 and 652 so as to prevent stress on the stitches which the associated needles hold. The long butt lower sliders follow the usual reciprocatory paths undergoing picking in the usual fashion by the pickers 686 and 688 to produce narrowing. In alternate reciprocations they pass down the forward and reverse stitch cams to take a main yarn. The picked up sliders pass above the level of the center cam 654 beneath the bottom of the raised cam 664. Cam 658 is at this time raised to avoid depressing action on the movable walls which would tend to stress rib stitches carried by needles in the upper cylinder.

During widening the lower picker is brought into operation, this involving temporary control of the lower picker to hold it between the two levels of passage of the long butt lower sliders. This control of the lowering picker need not be described herein, being described in detail in the Lawson and Bristow application referred to above.

The knitting of the toe is essentially similar to the knitting of the heel and the brief description offered above will suffice for both.

Various matters disclosed herein are claimed in Patents 2,569,706, 2,604,767 and 2,627,740, dated, respectively, October 2, 1951, July 29, 1952, and February 10, 1953.

What I claim and desire to protect by Letters Patent is:

1. A knitting machine comprising a needle cylinder, needles carried by said cylinder, a plurality of wrap yarn carriers, means for projecting said carriers outwardly across the needle circle at angularly spaced wrapping locations, and means for selectively returning said carriers inwardly across the needle circle at different angular spacings from their outward projections at each of said wrapping locations.

2. A knitting machine comprising a needle cylinder, needles carried by said cylinder, wrap yarn carriers, means for projecting said carriers outwardly across the needle circle, and yielding cam means engageable by said carriers when outwardly projected for restraining their outward movements.

3. A knitting machine comprising a needle cylinder, needles carried by said cylinder, a pair of wrap yarn carriers having yarn guides at their ends, and means for mounting said yarn carriers side by side with said ends closely adjacent to each other, one of said yarn carriers having means providing a laterally extending ear at its ends to engage the end of the other carrier to maintain said ends spaced apart.

4. A knitting machine comprising a needle cylinder, needles carried by said cylinder, a pair of wrap yarn carriers having yarn guides at their ends, means for mounting said yarn carriers side by side with said ends closely adjacent to each other, and means providing a rest, said carriers being resilient so that both normally flex to bring their ends towards said rest, one of said yarn carriers having means providing a laterally extending ear at its end to engage the end of the other carrier to maintain said ends spaced apart.

5. A knitting machine comprising spaced superposed

needle cylinders, needles carried by said cylinders, a pair of wrap yarn carriers having yarn guides at their ends, and means for mounting said carriers side by side and extending through one of said cylinders with said ends closely adjacent to each other and in the space between said cylinders, one of said carriers having means providing a laterally extending ear at its end to engage the end of the other carrier to maintain said ends spaced apart.

6. A knitting machine comprising spaced superposed needle cylinders, needles carried by said cylinders, a pair of wrap yarn carriers having yarn guides at their ends, means for mounting said carriers side by side and extending through one of said cylinders with said ends closely adjacent to each other and in the space between said cylinders, and means providing a rest, said carriers being resilient so that both normally flex to bring their ends towards said rest, one of said carriers having means providing a laterally extending ear at its end to engage the end of the other carrier to maintain said ends spaced apart.

7. A knitting machine comprising a needle cylinder, needles carried by said cylinder, a pair of wrap yarn carriers, means for mounting said carriers side by side, and means interengaging said carriers to limit relative radial movements thereof, said means comprising a member loosely located in openings in said carriers.

8. A knitting machine comprising a needle cylinder, needles carried by said cylinder, a pair of wrap yarn carriers, means for mounting said carriers side by side, means interengaging said carriers to limit relative radial movements thereof, means for projecting one of said carriers outwardly across the needle circle, and means for limiting outward movement of the other carrier, so that, through the restraint imposed by said interengaging means, the outward movement of the first mentioned carrier under the action of said projecting means is also limited.

9. A knitting machine comprising spaced superposed needle cylinders, needles carried by said cylinders, a pair of wrap yarn carriers, means for mounting said carriers side by side and extending through one of said cylinders, and means interengaging said carriers to limit relative radial movements thereof.

10. A knitting machine comprising spaced superposed needle cylinders, needles carried by said cylinders, a pair of wrap yarn carriers, means for mounting said carriers side by side and extending through one of said cylinders, and means interengaging said carriers to limit relative radial movements thereof, said means comprising a member loosely located in openings in said carriers.

11. A knitting machine comprising spaced superposed needle cylinders, needles carried by said cylinders, a pair of wrap yarn carriers, means for mounting said carriers side by side and extending through one of said cylinders, means interengaging said carriers to limit relative radial movements thereof, means for projecting one of said carriers outwardly across the needle circle, and means for limiting outward movement of the other carrier, so that, through the restraint imposed by said interengaging means, the outward movement of the first mentioned carrier under the action of said projecting means is also limited.

12. A knitting machine comprising superposed rotating needle cylinders, means carrying a wrap yarn for presentation to needles, means supporting said carrying means within the upper cylinder for rotation therewith, mounting means for said supporting means, the mounting means comprising an axially movable and rotatable member carrying said supporting means and constructed and arranged so that the supporting means with the wrap yarn carrying means may be lifted from the upper cylinder and laterally swung to an accessible location, and means for counterbalancing said axially movable member and the supporting means carried thereby.

13. A knitting machine comprising a needle cylinder, needles carried by said cylinder, wrap yarn carriers, cams acting on said wrap yarn carriers to move them to present yarns to needles, cams for selectively presenting needles in position to take wrap yarns, and a single element manipulable to render both sets of cams ineffective.

14. A knitting machine comprising a needle cylinder, needles carried by said cylinder, wrap yarn carriers, cams acting on said wrap yarn carriers to move them to present yarns to needles, cams for selectively presenting needles in position to take warp yarns, means yieldingly urging both

sets of cams towards operative positions, and a single element manipulable to render both sets of cams ineffective.

15. In a knitting machine having a needle bed and a relatively displaceable needle-operating means, needles in said bed, and a main feeder for feeding main thread to the needles to be knitted thereby course after course; wrap striping mechanism for patterning the fabric knitted of the main thread by knitting a plurality of wrap threads along with the main thread in selected needle wales, comprising a separate wrap finger for each wrap thread, means for giving said fingers, one after another, a wrapping traverse relatively to one and the same group of the needles at a time prior to that at which said needles clear their old loops, means for positioning, in each traverse and at a height less than the clearing height, only the wrap needle or needles required to receive wrap thread from the finger then traversing which height is such that the wrap thread is applied to each raised needle above the uncleared old loop on the needle, means for lowering prior to the second traverse such needle or needles as may have received wrap thread at the first traverse to a level such that these needles are not supplied with wrap thread from the second finger, means for supporting the applied wrap thread during such needle-lowering and for preventing its descent with such needle or needles, means for raising such needle or needles and for clearing the old loops from the needles without clearing the newly applied wrap threads, and means for operating the wrapped needles to take the main thread and to knit it with the wrap thread.

16. A knitting machine comprising superposed needle cylinders, needles carried by said cylinders, a plurality of means carrying wrap yarns for presentation to needles, said wrap yarn carrying means having overlapping ranges of yarn presentation in the formation of a single course, and means for effecting successive selective wrapping at spaced points by said wrap yarns on predetermined needles in the formation of a single course.

17. A knitting machine comprising superposed needle cylinders, needles carried by said cylinders, a plurality of means continuously carrying wrap yarns for presentation to needles, said wrap yarn carrying means having overlapping ranges of yarn presentation in the formation of a single course, and means for effecting selective wrapping by said wrap yarns on predetermined needles.

18. A knitting machine comprising superposed needle cylinders, needles carried by said cylinders, a plurality of means continuously carrying wrap yarns for presentation to needles, said wrap yarn carrying means having overlapping ranges of yarn presentation in the formation of a single course, and means for effecting successive selective wrapping at spaced points by said wrap yarns on predetermined needles in the formation of a single course.

19. A knitting machine comprising superposed needle cylinders, needles carried by said cylinders, a plurality of means carrying wrap yarns for presentation to needles, mounting means for said wrap yarn carrying means concentric with said cylinders, and means selectively producing long and short ranges of wrapping of said wrap yarn carrying means.

20. A knitting machine comprising superposed needle cylinders, needles carried by said cylinders, wrap yarn carriers, means controlling wrap yarn carriers at two wrap stations to present wrap yarns to needles, means for selectively moving needles at the first of said wrap stations to position to receive wrap yarn thereat, means for locating needles, including those receiving wrap yarn at said first station, at a common level at a position beyond said first station and in advance of the second of said stations, means for selectively moving needles at said second station to position to receive wrap yarn thereat, and means for thereafter moving needles to draw stitches including wrap yarns fed at both of said stations.

21. A knitting machine comprising superposed needle cylinders, needles carried by said cylinders, wrap yarn carriers, means controlling wrap yarn carriers at two wrap

stations to present wrap yarns to needles, means for locating needles at a common level in advance of said first station, means for selectively moving needles at the first of said wrap stations to position to receive wrap yarn thereat, means for locating needles, including those receiving wrap yarn at said first station, at a common level at a position beyond said first station and in advance of the second of said stations, means for selectively moving needles at said second station to position to receive wrap yarn thereat, and means for thereafter moving needles to draw stitches including wrap yarns fed at both of said stations.

22. A knitting machine comprising a needle cylinder, needles carried by said cylinder, main yarn feeding means, wrap yarn carriers, means controlling wrap yarn carriers at two wrap stations to present wrap yarns to needles at a time prior to that at which said needles clear their old loops, means for positioning at each of said stations at a height less than clearing height predetermined needles to receive the wrap yarns, so that the wrap yarns are applied to needles above uncleared old loops, means for lowering needles which have received wrap yarn at the first station before reaching the second station, means for supporting the wrap yarn applied at the first station during such lowering to prevent its descent with the needles, means for clearing the old loops from the needles without clearing newly applied wrap yarns, and means for moving the wrapped needles to take the main yarn and knit it with the wrap yarns.

23. A knitting machine comprising a needle cylinder, needles carried by said cylinder, main yarn feeding means, wrap yarn carriers, means controlling wrap yarn carriers at two wrap stations to present wrap yarns to needles at a time prior to that at which said needles clear their old loops, means for positioning at each of said stations at a height less than clearing height predetermined needles to receive the wrap yarns, so that the wrap yarns are applied to needles above uncleared old loops, means for supporting the applied wrap yarns to prevent downward movements thereof relatively to the needles to which they are applied, means for clearing the old loops from the needles without clearing newly applied wrap yarns, and means for moving the wrapped needles to take the main yarn and knit it with the wrap yarns.

24. A knitting machine comprising a needle cylinder, needles carried by said cylinder, a pair of wrap yarn carriers, means for mounting said carriers side by side, and means independent of said mounting means interconnecting said carriers to limit their radial displacements relative to each other.
